UNITED STATES PATENT OFFICE.

ARTHUR J. HELMS, OF PORTLAND, OREGON.

MITER-TOOL.

1,295,748.

Specification of Letters Patent. Patented Feb. 25, 1919.

Application filed May 21, 1917. Serial No. 169,958.

To all whom it may concern:

Be it known that I, ARTHUR J. HELMS, a citizen of the United States, residing in the city of Portland, county of Multnomah, and 5 State of Oregon, have invented certain new and useful Improvements in Miter-Tools, of which the following is a specification.

My invention relates to miter-tools of the character shown and described in my pending application filed August 3, 1916, Serial 10 Number 112,980, and has as its principal object to provide an improved construction and arrangement of miter tool of the character referred to, capable of many adjustments, whereby to cut any straight miter, and with which any straight saw can be 15 used.

Other objects and advantages will be apparent from the following description of 20 one practical embodiment of my invention taken in connection with the accompanying two sheets of drawings in which:—

Figure 1 is a top plan view of a miter tool embodying my invention;

Fig. 2 is a side elevation thereof, with parts shown in section;

Fig. 3 is a rear end view thereof;

Fig. 4 is a front end view thereof; and

Fig. 5 is a vertical cross sectional view 30 thereof taken on the line 5—5 of Fig. 1.

Referring now in detail to the drawings, my invention comprises a base plate 1, upon which is rotatably mounted a body 2, shown to be of cylindrical form and open at its 35 upper and lower ends and rotatably secured to the base plate 1, by means of an interior cross piece 3, and a bolt 4, as clearly shown in Fig. 5. Rotatably and detachably seated in the upper end of said body 2, is a horizontal bearing block 5, rotatably held against accidental misplacement by means of a thumb screw 6, through the side of the body 2, as clearly indicated. Revolubly seated in said horizontal bearing block 5, in 40 a vertical plane, is a vertical bearing block 7, dove-tailed into the horizontal bearing block 5, as indicated in Figs. 1, 2 and 5, said vertical bearing block 7, having a segment cut therefrom in order to provide a 45 seat for the forward end of a trough-like work-holder 8, the forward end of which is beveled, as at 8^a and 8^b, and the rear end of which is rotatably seated in a bearing standard 9, by means of a bearing ring 10, 50 said bearing ring 10 being adapted to be se-

cured in different rotated positions by means of a thumb screw 11.

It will be evident that the base plate 1, and the bearing standard 9, may be permanently secured to a work-bench, or other 60 support, if desired. It will also be evident that the trough-like work-holder can be turned to various angles about a longitudinal axis by simply loosening the thumb screw 11, and turning said work-holder 8, 65 by hand.

Formed as a part of the body 2, is a straight guide portion 2^a, recessed as at 2^b, whereby to form a passageway for a purpose hereinafter referred to. Slidably connected with said straight guide portion 2^a, is 70 a guide frame adapted to be moved longitudinally along the guide portion 2^a of the body 2, and also adapted to be locked against longitudinal movement by means of a bolt 75 13, extended through the body 2, and provided with a thumb nut 14, as clearly shown in Fig. 2, said bolt having a head 13^a seated in said guide frame 12, for holding it in locked position against the straight guide 80 portion 2^a of the body 2, as will be clear from Fig. 2. As said guide frame 12 is slidably secured to the body 2, it is capable of a longitudinal movement relative to said body 2, and also turns with said body 2, on 85 the base plate 1, about a vertical axis.

Adjustably secured to the face of the guide frame 12, are two vertical saw guides 15—15, held in place by means of bolts 16, provided with thumb nuts 17, said thumb 90 nuts moving through the passageway 2^b, in the straight guide portion 2^a of the body 2, as will be clear from Fig. 2, when said guide frame 12 is moved longitudinally in either direction. Said vertical saw guides 95 are adjustable longitudinally of said guide frame 12, in a slot 12^a, extending longitudinally through said guide frame 12. By loosening the thumb nuts 17—17, said vertical saw guides can be turned down along the 100 side of the guide frame 12, when not in use, or for packing purposes, as desired, or they can be wholly detached by simply removing the thumb nuts 17—17.

Slidably mounted in each of the vertical 105 saw guides 15—15, are saw holders 18—18, each having a saw receiving slot, as 19, open at its lower end, as clearly shown in Fig. 2, whereby any flat saw blade can be inserted thereinto and thereby held in a true 110

plane during its operation, said saw holders 18-18, being free to slide up and down vertically in said vertical saw guides 15, as the saw is operated.

- 5 Thus it will be seen that I have provided a very substantial and practical miter tool capable of every adjustment necessary for cutting miters of different angles. The piece being cut is laid longitudinally in the trough-like work-holder 8, so that the end thereof to be cut projects beyond the guide frame 12, and between the vertical saw guides 15-15, said work-holder 8 and the piece therein being capable of adjustment about 10 its longitudinal axis, as before described. Said work-holder 8, is provided on its opposite outer sides, at its forward end, with two angle pieces 8', adapted to act as stops when one side or the other of said work-holder is turned down to a horizontal plane, as shown in Fig. 2. The vertical guide members 15-15, can be spaced apart to suit the size of the piece to be sawed. The saw holders 18-18 can be raised sufficiently 15 to put the saw teeth across the top of the piece to be sawed, and the body 2, together with the guide frame 12, can be turned about a vertical axis to any desired angle relative to the end of the piece to be cut.
- 20 While I have shown and described one practical embodiment of my invention for purposes of illustration, I am aware that changes can be made therein without departing from the spirit thereof, and I do not, 25 therefore, limit the invention to the form thereof here shown, except as I may be limited by the hereto appended claims.

I claim:

1. A miter tool of the character referred 40 to comprising in combination, a base, a body rotatably mounted thereon, a bearing block mounted in said body and occupying a horizontal plane, a bearing block rotatably connected with said first mentioned bearing 45 block and turning in a vertical plane, a work-holder of angular form having one end supported in said vertical bearing block and adapted to turn therewith about its longi-

tudinal axis, means for rotatably supporting the opposite end of said work-holder, 50 and means mounted on said body and turning therewith about a vertical axis for holding a saw, substantially as described.

2. A miter tool of the character referred to comprising in combination, a base, a body 55 rotatably mounted thereon about a vertical axis, a bearing block rotatably supported in said body, in a vertical plane, to turn about a horizontal axis, a work-holder of angular form having one end supported in said vertical bearing block, means for rotatably supporting the opposite end of said work-holder, and adjustable saw-supporting means mounted on said body for operatively supporting a saw in a vertical plane, substantially as described. 60

3. In a miter tool of the character referred to, a supporting body, a bearing block rotatably mounted therein, in a horizontal plane, a second bearing block rotatably mounted in a 70 vertical plane in said first bearing block, a work-holder supported in said second bearing block, and also holding means adjustably mounted on said body for operatively holding a saw in a vertical plane, substantially as described. 75

4. In a miter tool, in combination, a base, a body rotatably mounted thereon, a bearing block rotatably mounted in said body in a vertical plane, a second bearing block rotatably mounted in said first bearing block, in a vertical plane, an angular work-holder supported by said second bearing block to turn therewith about a horizontal axis, a guide frame slidably secured to the said body, 80 spaced saw guides slidably connected with said guide frame, and saw holders having saw-receiving slots open at their lower ends to receive a saw, and slideable vertically in said saw guides, substantially as described. 85 90

Signed at Portland, Multnomah county, Oregon, this 15th day of May, 1917.

ARTHUR J. HELMS.

In presence of—

I. M. GRIFFIN,
J. C. STRENG.
